(57) **CLAIM**

The ornamental design for an instep strap for shoe, as shown and described.

DESCRIPTION

FIG. 1 is a perspective view of an instep strap for a shoe showing my new design

FIG. 2 is a left side elevation view of the instep strap for shoe shown in FIG. 1;

FIG. 3 is a right side elevation view of the instep strap for shoe shown in FIG. 1;

FIG. 4 is a top plan view of the instep strap for shoe shown in FIG. 1;

FIG. 5 is a bottom view of the instep strap for shoe shown in FIG. 1;

FIG. 6 is a front view of the instep strap for show as shown in FIG. 1; and,

FIG. 7 is a back elevation view of the instep strap for shoe shown in FIG. 1.

The broken lines depict portions of the instep strap for shoe in which the design is embodied and form no part of the claimed design.

1 Claim, 7 Drawing Sheets
